UNITED STATES PATENT OFFICE.

JOHN GERHARDT, OF MONTREAL, QUEBEC, CANADA, ASSIGNOR TO HIMSELF AND SAMUEL DAVIS, OF SAME PLACE.

COMPENSATION-PENDULUM.

SPECIFICATION forming part of Letters Patent No. 352,461, dated November 9, 1886.

Application filed June 5, 1886. Serial No. 204,218. (No model.)

To all whom it may concern:

Be it known that I, JOHN GERHARDT, of Montreal, in the Province of Quebec and Dominion of Canada, have invented a new and Improved Compensating-Pendulum, of which the following is a full, clear, and exact description.

The object of my invention is to provide an accurate and reliable compensating-pendulum which shall be cheap, durable, and not liable to get out of order.

To this end my invention consists, principally, of a compensating-rod and pendulum-rod, both made of the same metal, combined with pivoted connecting devices supported at one end by the compensating-rod, and from which the pendulum is suspended, so that the contraction of the compensating-rod will lower the pendulum and its expansion will raise the pendulum in exactly the degree that the pendulum itself expands and contracts under the influence of the same temperature with the compensating-rod.

The invention also consists of means for adjusting the compensating-rod, whereby the said rod may be used as a regulator for the pendulum.

The invention also consists of the construction, arrangement, and combination of parts, all as hereinafter described and claimed.

Reference is to be had to the accompanying drawings, forming a part of this specification, in which similar letters of reference indicate corresponding parts in both the figures.

Figure 1 is a front elevation of my new and improved compensating-pendulum, and Fig. 2 is an edge view of the same.

A represents the compensating-rod, which is made of the same metal as the pendulum B, or of a metal that expands and contracts under the influence of heat and cold in equal degree with the metal of the pendulum. The compensating-rod A is supported upon the projection C, so that any contraction or expansion of said rod will show at its upper end. Connected to the upper end of the compensating-rod A is the lever D, pivoted at d.

The pendulum B is connected to the lever D by the short lever E and the connecting-link F, so that the up-and-down movement of the lever D, caused by the expansion and contrac-

tion of the compensating-rod A, will raise and lower the pendulum B. The rod A should be of suitable length, and the levers D E should be so arranged that the movement of the free end of the lever E will be just equal to the expansion and contraction of the rod A, so that when the rod A and pendulum contract the lever E will be lowered to compensate for the contraction of the pendulum, and when the pendulum B and rod A expand the lever E will lift the pendulum an equal degree, and thus accurately compensate for the effect that changes in temperature may have upon the pendulum. The pendulum is connected to the end of the lever E by the thin spring a, which is held between the opposite points b b, which constitute the point of oscillation of the pendulum, so the length of the pendulum is calculated from these points to its lower end. For regulating the length of the pendulum to increase or diminish its speed of oscillation, the ball c is not raised or lowered upon its rod as with a common pendulum, but the compensating-rod A is raised or lowered by turning the nut d', which will communicate a like movement to the pendulum through the levers D E. An index, f, and pointer g are combined with the rod A to assist in regulating the pendulum.

Constructed as described, the pendulum is not only accurately self-compensating, but is cheap, and not liable to get out of order, and serves also as the regulating-rod for the pendulum.

Having thus described my invention, what I claim as new, and desire to secure by Letters Patent, is—

1. The combination, with the pendulum, of the supported compensating-rod and the intermediate lever-connection, comprising a lever connected to the compensating-rod and a second lever connected with the aforesaid lever and with the pendulum, substantially as and for the purpose set forth.

2. The combination, with the pendulum B, of the compensating-rod A, supported upon the projection C, and connected to the pendulum by the connected levers D E, the pendulum-spring being held between the points b, substantially as described.

3. The compensating-rod A, made longi-

tudinally adjustable, in combination with the pendulum and the pivoted connected and connecting levers D E, substantially as and for the purposes described.

5. 4. The combination, with the compensating-lever A and adjusting-nut d , of the index f and pointer g , substantially as described.

5. The combination, with the compensating-rod having a pointer and the apertured bracket

or support, of the nut working and supported in said bracket or support and upon said rod, and the index, substantially as and for the purpose set forth.

JOHN GERHARDT.
